UNITED STATES PATENT OFFICE.

JAMES M. TAYLOR, OF OMAHA, NEBRASKA.

ELECTRIC-RAILWAY SYSTEM.

SPECIFICATION forming part of Letters Patent No. 650,997, dated June 5, 1900.

Application filed August 29, 1899. Serial No. 728,913. (No model.)

To all whom it may concern:

Be it known that I, JAMES M. TAYLOR, a citizen of the United States, residing at Omaha, in the county of Douglas and State of Nebraska, 5 have invented new and useful Improvements in Electric-Railway Systems, of which the following is a specification.

This invention relates to certain new and useful improvements in electric-railway systems; and it consists in the general construction and arrangement of the parts, more particularly the means, as will be hereinafter set forth, for supporting a car from a motor-truck positioned within an underground conduit.

15 In the accompanying drawings, which illustrate my invention, Figure 1 is a longitudinal sectional view showing the conduit or subway having tracks therein for the motor, a standard which extends from the motor through the slot, and means for connecting the car-body to the standard and to the center-bearing truck, also brakes and electric connections. Fig. 2 is a vertical sectional view. Fig. 3 is a 20 sectional view on the line 3 3 of Fig. 1 looking toward the slot or downward, said section also showing the position of the brake-levers. Fig. 4 is a sectional view on the line 4 4 of Fig. 1 looking upward. Fig. 5 is a top plan view of a disk carried by the upper end of the 25 standard or supporting-post, and Fig. 6 is a bottom plan view of the disk or supporting-plate attached to the frame of a car-body.

The underground conduit or subway is 30 preferably made up of cast-iron braces A, which may have therethrough openings, as a, to receive and support wires for a return-circuit and for other uses. The upper ends of the braces converge, and between them is a slot. The upper ends of the braces are curved 35 in the segment of a circle on their inner sides, and to the same are attached castings a', which, with the upper ends of the braces, provide recesses for the reception of slot-closing plates a² and springs for projecting said 40 plates from the curved slot or housing, so that when the springs are not compressed the plates will be projected to abut against each other and close the main slot or opening. It will be noted that the slot-closing 45 plates will extend slightly above the upper ends of the braces and form an arched surface, which will better resist weight or pres-

sure thereon from street traffic than an ordinary flat slot-closer with hinged plates. The slot-closing plates are made up of short 55 sections, and the supports therefor may have suitable openings, so that dirt or street-refuse will not collect beneath said plates.

The lower part of the conduit may be in the form of a trough and at suitable intervals will be connected with the sewer system and in the bottom of the conduit, so as to rest upon cross-ties A' and stringers A², to which are attached rails A³, upon which travels the motor-truck B. The lower inner walls of the 60 conduit subway or tunnel are preferably vertical, and said conduit need not greatly exceed the width of the truck which travels therein.

Upon the rails A³ within the conduit is a 70 four-wheeled truck, one of the pair of wheels of said truck having a driving-gear b, attached to the axles of the driving-wheels, said gear being driven by a gear b', which is turned by the motor B', said motor receiving a current 75 of electricity from a wire A⁴, suitably suspended within the conduit to be engaged by a trolley B², which is mounted on an arm, said arm being spring-actuated toward the feed-wire A⁴. The motor and electric connections are of ordinary construction, such as are used upon electrically-propelled cars, and the wires for controlling the current from the trolley to the motor are also of the ordinary type and arrangement and may pass to 80 the car rear of one of the standards which connects the motor-truck, which is provided with center bearings, with the car.

C refers to the longitudinal beams of the truck-frame, and near their ends said beams 90 C are connected by cross-beams C' C² C³. The hangers for the car-axle are attached to the longitudinal beams C, and the motor B' is suspended by hangers or straps attached to transverse beams C' C³, the motor being bolted 95 to the lower horizontal portions thereof. Near the center of the truck-frame B is a transverse beam C⁴, which carries centrally a fixture or casting with slotted ends and horizontal apertures, to which are bolted brake-levers 100 D D'. The lower ends of the brake-levers are connected to brake-bars d, which carry the usual brake-shoes, said bars being connected by straps d', which extend to the transverse

beam C' of the frame, and rods also extend from the brake-bars to the levers at points above their fulcrums. By the arrangement shown all of the brake-shoes may be operated 5 or brought in contact with the supporting-wheels by operating one of the levers. The levers are made up of flat bars, and their upper ends pass through the slots and have connected thereto rods for operating the levers 10 from the car. From the ends of the truck-frame project similar standards or posts E, and said posts are braced by angle-bars e e, which are bolted to the sides of the posts and to the longitudinal beams, there also being 15 angle-braces e', which extend from the front and rear of the post or standard and are attached to the transverse beams c' c'. The post or standard E is made up of a beam having a central web and lateral flanges, the 20 flanges being at right angles with the slot, and said beam is of sufficient length to extend near the floor of the car.

The beam E has bolted thereto by bolts which pass through the forward flanges a plow 25 F, the sides of which converge, and said beam or standard carries on a line with the plow and opposite the slot-closing plates flat bars, which extend from one standard to the other and serve to hold the slot-closing plates depressed 30 against the action of their closing-springs during the passage of a car. Between the flat bars F' the brake-levers D D' pass, as well as the electrical connections from the car to the motor. It will be noted that the 35 flat plates or bars F' abut against the ends of the flanges of the post or standard E and prevent the wearing away or injury to said standard by abrasion of the plates which close the slot or the side walls of the slot with the 40 same.

The closing plates or covers for the slots can be removed when it is desired to replace them by either sliding said plates longitudinally to a suitable opening in the upper portion 45 of the conduit or by the use of a suitable tool forcing one of the plates against the action of the spring and drawing the other one—that is, the one to be removed—beyond the curved slot in the upper portion of the 50 brace.

To the upper end of the standard is attached a disk G, which has an upwardly-projecting cylindrical portion located immediately above the upper end of said standard, 55 and the sides incline downward and are provided with recesses g, which form seats for springs h. The disk G is bolted to beams G', which are in turn bolted to the upper end of the standard by ties and to horizontal cross-beams G², the inner ends of which are bent at an angle for engagement with the flanges of the standards. The ends of the beams G² or angle-braces are bent downward, as shown in Fig. 2, and bolts pass through said ends, 60 65 the heads of the bolts entering countersunk openings at the bottom of the recesses g.

Lateral brace-beams G³, which are connected to the beams or bars G' G² by the bolts hereinbefore mentioned, have their ends bent to engage the web of the post or standard at a point opposite and above the slot of the conduit, and the bolts which connect the parts may also serve to hold the flat bars F', hereinbefore mentioned, thereto. To the car-floor are secured transverse beams, to which 70 75 is connected a disk H, having a central aperture and peripheral grooves in which the upper ends of the springs are seated. The two conical disks G and H may be suitably connected not to interfere with the turning 80 of the car upon the posts or standards connected to the trucks.

By the construction shown a car-body is supported from a power-driven truck located within a conduit, surface tracks are avoided, 85 and after the car has passed a given point the slot is automatically closed, and the entire running-gear being underground will be protected from the elements, so that there will be no liability of traffic being suspended on 90 account of storms, and the tracks will be protected from wear and tear other than what is incident to the passing of wheels over the rails. The particular construction set forth thoroughly braces the posts or standards, and the 95 slot prevents the standards assuming other than a vertical position, and there is sufficient play provided between the car and the car-supports carried by the standards to permit the car-body rounding curves, and with 100 the arrangement shown a comparatively-short motor-truck may support a long car, so that sharp turns can be made.

What I claim as new, and desire to secure by Letters Patent, is— 105

1. The combination with an underground conduit having therein parallel tracks, of an electrically-propelled motor and car carrying truck provided with vertical standards which are rigidly attached to the motor-truck, bearing-plates forming a part of a center-bearing truck for the car-body attached to the upper ends of the standards, braces which extend from said bearing-plates downward and are attached to the standards at points opposite 110 115 the walls of the slot of the conduit, substantially as shown.

2. The combination with an underground conduit having a longitudinal slot, automatic slot-closers, of a motor-truck located in the 120 conduit and provided with vertical standards and brake-levers which extend through the slot, a slot-opener carried by the standards, plates attached to the standards on a line with the slot-closers, the brake-levers extending through the slot between the plates, substantially as shown.

3. The combination in an underground electric-railway system, of a conduit having parallel tracks therein and a slot therethrough, 125 130 a motor-truck having a vertical standard with a central web and lateral flanges, a center

bearing-plate for the car-body rigidly attached to the standard and provided with lateral brace-beams, the lower ends of the beams being bent to lie between the lateral flanges 5 of the standards at a point opposite the side walls of the slot through the conduit, substantially as shown.

4. In an underground electric-railway system, a conduit in which the motor-truck travels, standards attached to the truck, a center bearing carried by the upper end of the standard, a bearing for engagement therewith attached to the car-frame, a shoe carried by and in advance of the standard, brake-levers pivotally attached to the motor-truck within the conduit, rods connected to the levers, the levers extending through the slot of the conduit and means for actuating the levers from without the conduit, substantially as shown.

5. In an underground electric-railway system, a conduit having motor-truck and car supporting tracks therein, a motor-truck having standards which are attached centrally thereto and extend upward through the slot of the conduit, center bearing-disks attached to the upper ends of the standards, braces connected to said disks and at points opposite the slot to the standard, bearing-plates 25 attached to the car-body and springs between the sections of the bearing-plates, substantially as shown.

6. In a closed-conduit system of electric propulsion for cars, a motor-truck adapted 35 to travel upon tracks within a conduit and support therefrom a car-body, the means for connecting the car-body and motor-truck including center bearing-plates and means whereby the car-body can have a movement 40 independent of the motor-truck, and brake mechanism carried by the motor-truck which

is adapted to be actuated from the car, substantially as shown.

7. In an electric-railway system, the combination with a car, of a motor-truck to which 45 are rigidly attached standards having longitudinal webs and flanges the flanges being at right angles to the webs, center bearing-plates mounted on the upper ends of the standards and braced thereto, a pair of the braces having their lower ends bent to lie parallel with the web and between the flanges of the standards, bearing-plates attached to the car-body for engagement with the bearing-plates of the standards, substantially as shown whereby 55 the car-body may have a limited movement independent of the motor-truck, substantially as set forth.

8. In an electric-railway system which includes an underground conduit with motor 60 and car supporting tracks therein, a slot located above and between the tracks, standards rigidly attached to the motor-truck so as to project through the conduit, a car-body supported from said standards, shoes and 65 plates carried by the standards on a line with the side walls of the slot, a pair of brake-levers pivotally attached to the motor-truck and connected on each side of their centers to brake-shoes, said brake-levers extending 70 between the standards and plates carried thereby above the slot and means which extend toward each end of the car, substantially as shown and for the purpose set forth.

In testimony whereof I have hereunto set 75 my hand in presence of two subscribing witnesses.
